CLAIM

The ornamental design for a pet hair removing brush, as shown and described.

DESCRIPTION

FIG. 1 is a front perspective view of a pet hair removing brush in accordance with the present design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view thereof.

The broken lines shown in the drawings illustrate features of the article that form no part of the claimed design.
